Primary Examiner — Leanne Was-Englehart*Assistant Examiner* — Yelizaveta Y Masalimova(74) *Attorney, Agent, or Firm* — Kilpatrick Townsend & Stockton LLP**CLAIM**

The ornamental design for a shoe as shown and described.

DESCRIPTION

The FIGURE is a bottom view of a shoe, showing my new design.

The dot dashed broken lines represent a boundary of the claimed design and form no part thereof. Portions of the shoe outside of the boundary form no part of the claimed design.

1 Claim, 1 Drawing Sheet(56)
